UNITED STATES PATENT OFFICE.

GEORGE L. RICE, OF CHICAGO, ILLINOIS, ASSIGNOR, BY MESNE ASSIGNMENTS, TO INTERNATIONAL HARVESTER COMPANY, A CORPORATION OF NEW JERSEY.

MACHINE AND METHOD FOR MAKING COMBINATION PAPER-FIBER TWINE.

1,320,921.

Specification of Letters Patent.

Patented Nov. 4, 1919.

Original application filed November 8, 1917, Serial No. 200,896. Divided and this application filed April 13, 1918. Serial No. 228,494.

To all whom it may concern:

Be it known that I, GEORGE L. RICE, a citizen of the United States, residing at Chicago, in the county of Cook and State 5 of Illinois, have invented certain new and useful Improvements in Machines and Methods for Making Combination Paper-Fiber Twine, of which the following is a full, clear, and exact specification.

10 This application is a division of application Serial No. 200,896, filed November 8, 1917, and the invention forming the subject matter of this application relates to machines and methods for making combination 15 paper-fiber twine.

I am well aware that there are many twines of this general type on the market which are made by covering a fiber center with paper, but in all cases the fiber center 20 is spun into a yarn previous to covering the same with the paper. In other words, the spinning of the fiber center and the combining of the fiber with the paper are two separate and distinct operations. When the 25 spun center and paper are being put together in this manner the tension on each is separately regulated, and the number of twists in the fiber center is entirely independent of and usually differs from the 30 number of twists in the paper covering or sheath. The twine made in this manner is defective since there is no intertwisting or interlocking of the fiber and the paper, and the paper covering is, therefore, easily 35 stripped from the fiber center. Moreover, the difference in the number of twists per unit of length in the fiber center and paper cover, and the fact that the fiber center, having previously been twisted into a 40 twine, receives additional twist when the paper cover is applied, results in a twine which is stiff and kinky, and unsuitable when employed in such manner that it must be fed through guiding eyes or employed in 45 binding and knotting machines.

The object of my invention is to provide a strong and flexible paper fiber twine having sufficient weather proofing and insect 50 proofing qualities to meet the ordinary conditions, and more particularly the conditions encountered in the use of such twine in harvesting machinery, and moreover to

provide a twine which will not kink and in the use of which the paper covering will not be stripped from the fiber.

55

With the above object in view my invention is embodied in a machine for making the paper-fiber twine in which the elements are interlocked and intertwined.

My novel machine comprises means for 60 feeding the paper and non-twisted fiber, means for folding the paper about the fiber, preferably in such a manner that the paper will entirely cover the fiber and that portions of the fiber will be disposed in longitudinal creases in the paper which may be formed by the paper feeding and folding means, and means for spinning or twisting the paper and fiber together.

In a more specific form the machine may 70 embody the elements enumerated below, although it should be distinctly understood that it is not essential that all of these elements be present for the successful operation of the machine.

75

The machine in its more specific form, then, embodies means for simultaneously drawing and feeding untwisted fiber and a ribbon of paper, means for slightly condensing the fiber into a loose core and for 80 forming the paper into a tube around this core, means for crushing or crimping the paper onto the loose fiber core in such a manner that some of the fibers of the loose core are disposed in the longitudinal seams 85 formed by the crushing means, and means for simultaneously twisting the untwisted fiber and crimped paper together to form the combination paper and fiber twine in which the paper covering is interlocked and 90 intertwined with the fiber core.

In the accompanying drawings I have illustrated one embodiment of my invention, and in these drawings,—

Figure 1 shows a side elevation of the improved paper twine machine;

Fig. 2 shows an enlarged detail view, partly in section, of the feeding, forming and crushing mechanism;

Fig. 3 shows a front elevation of the 100 moistening mechanism for the paper, and of the positive driving mechanism for the moistening roll;

Fig. 4 is a top plan view of the former;

Fig. 5 is a front elevation of the construction shown in Fig. 4;

Fig. 6 illustrates one step in the method of forming the twine; and

5 Fig. 7 is a perspective showing the twine formed by my improved method and machine.

The usual type of horizontal flier spinning machine is employed, and this machine embodies a supporting frame 10, the usual flier frame 11, bobbin 12, and capstan pulleys 13. The paper is carried on a reel 14, supported by the main frame, and passes over an idler pulley 15 and a moistening roller 16, which are supported by the supply tank 17 for the moistening liquor. The roller 16 is positively driven by means of the gearing 18, 19 and 20, the gear 20 being mounted on a pintle 21 which also 10 carries a sprocket 22, which meshes with the feeding mechanism for the sliver. This feeding mechanism for the fiber comprises the usual gill bars 23 and gill pins 24, driven in the usual manner. By means 15 of this sprocket 22 and the intermediate gearing which is supported by the tank 17, I have provided a positive drive for the moistening roller 16, and in this manner the amount of moisture fed to the paper strip 20 25 can be positively controlled. The liquid in the tank 17 may consist simply of water, or an emulsion of water and oil, preferably animal or mineral oil, with which the paper may be treated to make it weather proof 30 and insect proof. It is, however, not absolutely essential that the paper be treated with oil since the fiber is always treated with oil, and the intertwisting of the fiber and paper forces and squeezes the oil outwardly into the paper.

The feeding and drawing mechanism for the ribbon of paper and the sliver is substantially the same as that shown in my Patent, No. 1,217,067, granted February 20, 45 1917, and consists of a large feeding roller 26 mounted above two small feeding rollers 27 and 28, the rollers 27 and 28 being positively driven by suitable gearing mechanism. The shaft for the roller 26 is journaled in a box 29, slideable in a supporting bracket 30, pivoted at 31 to a fixed part of the frame. I have provided suitable means 50 by which the roller 26 may be lifted out of contact with the rollers 27 and 28, and this means comprises a link 32 suitably pivoted to a handle or lever 33, which in turn is pivoted at 34 to a fixed part of the frame. When it is desired to obtain access to the feeding rollers the arm 33 is lifted 55 and swung about the pivot 34 until the stop 60 contacts with a portion 36 of the main frame, thereby raising the roller 26.

The ribbon 25 of paper after leaving the moistening roller 16 passes around an idler 65 37 carried by the main frame, and through

a suitable guide 38, which rests on the roller 27 and is supported at its upper end by a lug 39 carried by the main frame.

From the above description it will be seen that the flat paper ribbon and the non-twisted sliver are positively and simultaneously fed through the machine, the rollers 70 26, 27 and 28 having the same drawing action described and claimed in my Patent No. 1,217,067 above referred to. By means 75 of this simultaneous feeding the tension on the paper and the sliver is maintained uniform, and this is a distinct advantage in that it avoids any tendency in the completed paper twine to break through unequal 80 strains. After passing through the feeding rollers 26, 27 and 28 the paper ribbon and the loose fiber core are passed through a former 40, the main body portion of this former having the shape of a hollow cone. 85 This conical body portion is provided with laterally projecting lugs 41, having slots 42, which are provided with suitable securing means for clamping the former to the frame of the spinning machine. On the inside of 90 this conical body there is secured a guide 43 for the non-twisted fiber, this guide consisting of a grooved or concave member, the side walls of which converge toward the front of the cone for the purpose of condensing the sliver.

From an inspection of Fig. 2 it will be seen that the front end of this member 42 is disposed substantially in a line with the contacting surfaces of the feed rollers 26, 27 and 28, so that the sliver is not deflected materially out of the plane in which it is fed to the former. The paper after it leaves the feed rollers, as is clearly shown in Fig. 2, is positively fed into the former and 100 contacts with the upper wall of the conical body portion, and this wall forms the flat ribbon into a tube, as illustrated in Fig. 6. This tube is wrapped around the loose fiber core and is crimped into longitudinal 110 folds or creases 46, and the tube and the core are simultaneously fed forward to a crusher 44 and nipper 45, similar to the corresponding members shown in my patent above referred to. By means of the crusher 115 and nipper the tube is further crimped and crushed on to the fiber, as shown at 47 in Fig. 6, and the fiber is forced into the creases of the paper. The nipper 45 further condenses and compresses the tube and loose 120 fiber core, interlocks the paper and fiber, as is shown in Figs. 2 and 6, and upon leaving the nipper the paper and fiber are twisted together, forming the combination paper twine illustrated in perspective in 125 Fig. 7.

It is important to note that neither the fiber nor the paper is twisted separately, and that substantially no twisting action takes place until the fiber and paper have 130

- been crushed together and leave the nipper 45, when the two elements are simultaneously twisted together, and in this way a twine is provided in which the two elements 5 are simultaneously twisted together, thereby forming a twine in which the two elements making up the same have the same number of twists per unit of length. By means of this simultaneous feeding the tension on the 10 paper and fiber is maintained uniform, and this is a distinct advantage in that it avoids any tendency in the completed twine to break through unequal strains, and also aids in interlocking the inner fiber core and 15 paper covering together. Moreover, by twisting the two elements together simultaneously, forming a unitary structure, I have also succeeded in producing a twine, the elements of which will not be separated 20 from each other by stripping even when the twine is subjected to severe and unusual use.
- While I have in this application disclosed one embodiment which my invention may assume, it should be understood that the invention is capable of many modifications, 25 and that such modifications may be employed without departing from the spirit and scope of my invention, as expressed in the following claims:
- 30 1. In a machine for making twine, the combination of means for feeding non-twisted fiber and a ribbon of paper, and means for longitudinally creasing said paper about the fiber and disposing a portion 35 of the fiber in the longitudinal creases.
2. In a machine for making twine, means for wrapping a paper ribbon about a loose non-twisted fiber core, and for creasing the paper longitudinally, whereby the non- 40 twisted fiber is disposed within the creases in said paper.
3. In a machine for making twine, a former, means in advance of said former for feeding non-twisted fiber and a ribbon of 45 paper into said former, and means for simultaneously twisting and interlocking the paper and fiber.
4. In a machine for making twine, the combination of means for feeding a ribbon 50 of paper and non-twisted fiber, means for longitudinally crimping the paper about the fiber to form a tube, and means for compressing the crimped paper tube into the non-twisted fiber.
- 55 5. In a machine for making twine, the combination of positive feeding and drawing means for non-twisted fiber and a ribbon of paper, a former for condensing the fiber and folding the paper about said fiber, 60 a nipper for gripping the folded paper and further condensing the fiber, and means for simultaneously spinning the paper and fiber together.
6. In a spinning machine, positive feeding 55 means for non-twisted fiber and a ribbon
- of paper, a former having means for condensing said fiber to a core, and having means for wrapping the paper ribbon about said core, means for gripping the paper and fiber core, and means for simultaneously 70 twisting said paper and fiber to form a twine.
7. In a machine for making twine, means for supporting a paper ribbon, means for feeding non-twisted fiber, means for moistening said paper ribbon, and operative connections between said fiber feeding means and said moistening means whereby a constant relation is maintained between the speed of said moistening means and the 75 speed of said feeding means.
8. In a machine for making twine, means for feeding non-twisted fiber, means for supporting a ribbon of paper, a moistening roller disposed in the path of said paper ribbon, means for positively regulating the speed of said moistening roller, said means including operative connections between said fiber feeding means and said moistening 80 roller.
9. In a machine for making twine, means for feeding non-twisted fiber, means for supporting a ribbon of paper, moistening means for said ribbon, and means controlled by said fiber feeding means for regulating 85 the amount of moisture fed to said paper.
10. In a machine for making twine, the combination of means for positively engaging and feeding a ribbon of paper and non-twisted fiber, and a former disposed in the 100 path of said paper and fiber, said former having means for condensing the fiber and for forming the paper into a tube about said condensed fiber.
11. In a machine for making twine, the 105 combination of means for simultaneously feeding a ribbon of paper and non-twisted fiber, and a former disposed in the path of said paper and fiber, said former comprising a main body in the shape of a hollow cone 110 and a member having a longitudinal groove therein secured to the inner surface of said cone.
12. In a machine for making twine, spinning mechanism, and means for gripping 115 and drawing non-twisted fiber and for feeding said fiber and a ribbon of paper to said spinning mechanism at a uniform tension.
13. In a machine for making twine, spinning mechanism, and means for positively 120 and simultaneously engaging and feeding a ribbon of paper and non-twisted fiber to said spinning mechanism.
14. In a machine for making twine, spinning mechanism, and single means for positively and simultaneously engaging and feeding a paper ribbon and non-twisted fiber 125 to said spinning mechanism.
15. In a machine for making twine, spinning mechanism, means for feeding non- 130

- twisted fiber, and single means in the path of said fiber for crushing a paper ribbon and said fiber together and positively feeding the crushed ribbon and fiber forward.
- 5 16. In a machine for making twine, means for feeding a ribbon of paper and non-twisted fiber, and means disposed in the path thereof for condensing said fiber and crimping the paper around said condensed fiber.
- 10 17. In a machine for making twine, means for feeding a ribbon of paper and non-twisted fiber, means for crimping said paper, and means disposed within said last named means for condensing said fiber.
- 15 18. In a machine for making twine, means for feeding a ribbon of paper and non-twisted fiber, and a former disposed in the path of said paper and fiber, said former comprising a main body portion in the shape of
- 20 a hollow open-ended cone, and a concave member disposed within said cone having converging side walls.
19. In a machine for making twine, the combination of a nipper, means for positively feeding to said nipper a paper ribbon and a sliver of non-twisted fiber of proper size to produce twine of the desired tensile strength, and means for pulling said sliver and paper ribbon through the nipper and
- 25 twisting them into a twine after they pass through the nipper.
20. In a machine for making twine, the combination of a source of fiber supply and a source of paper supply, a nipper, means for drawing the fiber and paper from their source of supply and reducing a sliver of fiber to proper size to produce twine of the desired tensile strength and for feeding the sliver and paper positively to the nipper,
- 30 and means for pulling the sliver and paper through the nipper and twisting them together to form twine.
21. In a machine for making twine, the combination of a nipper, means for positively feeding to said nipper a paper ribbon and a sliver of fiber, and means for pulling the sliver and paper through the nipper and twisting them into twine after they pass through the nipper.
- 35 22. In a machine for making twine, means for simultaneously feeding a ribbon of paper and a sliver, a nipper, and means disposed between said nipper and said feeding means for condensing the sliver to a loose fiber core
- 40 55 and for crimping the paper about the said core.
23. In a machine for making twine, means for positively engaging and feeding non-twisted fiber and a ribbon of paper, and
- 45 60 means for twisting said fiber and paper together in such a manner that the paper entirely covers the fiber.
24. In a machine for making twine, means for positively engaging and feeding non-twisted fiber and a ribbon of paper, and
- 65 means for twisting said fiber and paper together in such a manner that the same number of twists will be formed in each per unit of length.
25. In a machine for making twine, means for positively engaging and feeding non-twisted fiber and a ribbon of paper, means for forming a series of spiral folds in said paper and disposing portions of said fiber within the folds of said paper.
26. In a machine for making twine, a former, and means in advance of said former for feeding non-twisted fiber and a ribbon of paper into said former.
27. In a machine for making twine, a substantially horizontally disposed former, and means for engaging and feeding non-twisted fiber and a ribbon of paper into said former.
28. In a machine for making twine, a hollow former having a substantially horizontally disposed passage therethrough, and means for engaging and feeding non-twisted fiber and a ribbon of paper into said former.
29. In a machine for making twine, a substantially horizontally disposed former, and means in advance of said former for feeding non-twisted fiber and a ribbon of paper in contact with each other and into said former.
30. In a machine for making twine, a substantially horizontally disposed former, and means including a plurality of feeding rolls for engaging and feeding non-twisted fiber and a ribbon of paper in contact with each other and into said former.
31. In a machine for making twine, a substantially horizontally disposed former, a nipper disposed adjacent and in longitudinal alignment with said former, and means in advance of said former for feeding non-twisted fiber and a ribbon of twine through said former to said nipper.
32. The method of forming a twine, which consists in crimping a paper ribbon about a non-twisted fiber core, disposing a portion of said fiber core within the crimps of said paper and twisting the fiber and paper together.
33. The method of forming a twine, which consists of positively feeding a ribbon of paper and non-twisted fiber, crimping the paper into the fiber, and simultaneously twisting the fiber and paper.
34. The method of forming a twine which consists of feeding a ribbon of paper and non-twisted fiber, longitudinally creasing the paper about the fiber to form an envelop, disposing a portion of the fiber in the longitudinal creases and twisting the fiber and paper envelop together.
35. The method of forming a twine, which consists in crimping a paper ribbon into a non-twisted fiber core, and simultaneously twisting the paper and fiber together.

36. The method of forming a twine, which consists in simultaneously feeding a ribbon of paper and non-twisted fiber, crimping said paper longitudinally to form 5 a tube about said fiber, compressing said tube on to the fiber whereby a portion of the fiber is disposed within the longitudinal crimps of said paper tube and twisting the paper and fiber together.
- 10 37. The method of forming a twine, which consists in simultaneously feeding a ribbon of paper and non-twisted fiber, longitudinally crimping the paper into the fiber and forming the ribbon into a tube about 15 the fiber to form an envelop, and simultaneously twisting the tube and fiber together.
- 20 38. The method of forming a twine which consists of positively feeding a ribbon of paper and non-twisted fiber, condensing the fiber to a core, folding the paper about said core, and crimping the paper longitudinally so as to grip individual fibers of the core, and simultaneously twisting the paper and fiber together.
- 25 39. The method of forming a twine which consists of crimping a ribbon of paper lon- gitudinally to form inwardly projecting folds gripping individual fibers between adjacent inwardly projecting folds and twisting the fiber and paper together. 30
40. The method of forming a twine which consists of covering untwisted fiber with paper, crimping the paper longitudinally to form folds, gripping individual fibers in said folds and twisting the fiber and paper 35 together.
41. The method of forming a twine which consists of positively and simultaneously engaging and feeding a ribbon of paper and non-twisted fiber in contact with each other and at a uniform tension into a forming tool, of drawing the paper and fiber through the forming tool to fold the paper into a tube about the fiber, crimping the paper tube into the fiber while maintaining 40 both paper and fiber in untwisted condition, and then twisting the paper and fiber together. 45

In testimony whereof I affix my signature.

GEORGE L. RICE.
